DESIGN FOR A TOOTHBRUSH

Walter W. Hadley, Richmond, Calif.

Application July 9, 1934, Serial No. 52,501

Term of patent 14 years

To all whom it may concern:

Be it known that I, Walter W. Hadley, a citizen of the United States, and a resident of Richmond, in the county of Contra Costa and State of California, have invented a new, original, and ornamental Design for a Toothbrush, of which the following is a specification, reference being had to the accompanying drawing, forming part thereof, wherein

Figure 1 is a side elevation of a toothbrush embodying my new design.

Figure 2 is a back view of the toothbrush.

The exposed surfaces of the brush block are of a light shade of color. The exposed surface of the ferrule member of the brush assembly is of polished metal and the handle is of a color contrasting with the said ferrule member.

I claim:—

The ornamental design for a toothbrush, substantially as shown and described.

WALTER W. HADLEY.
